UNITED STATES PATENT OFFICE.

ALFRED BLANCHARD AND FRANK H. GATES, OF WARE, MASSACHUSETTS.

STOP-MOTION FOR KNITTING-MACHINES.

SPECIFICATION forming part of Letters Patent No. 764,338, dated July 5, 1904.

Application filed October 13, 1903. Serial No. 176,879. (No model.)

To all whom it may concern:

Be it known that we, ALFRED BLANCHARD, of No. 11 Main street, and FRANK H. GATES, of No. 50 Park street, Ware, in the county of Hampshire and State of Massachusetts, have jointly invented certain new and useful Improvements in Stop-Motions for Knitting-Machines; and we do hereby declare that the following is a full, clear, and exact description thereof, reference being had to the accompanying drawings, forming a part of this specification, and in which—

Figure 1 represents a top or plan view of so much of a knitting-machine as is necessary to illustrate our improvements. Figs. 2 and 3 are side views thereof looking in the directions of arrows *a* and *b*, respectively. Fig. 4 is an inner end view looking in the direction of arrow *c*, Figs. 2 and 3. Fig. 5 represents, upon an enlarged scale, a plan of my improved stop-motion device hereinafter described, Figs. 6, 7, 8, and 9 being upon the same enlarged scale. Fig. 6 is a side view of the parts shown in Fig. 5 looking in the direction of arrow *d* in said Fig. 5. Fig. 7 is a plan view of the outer half of Fig. 5 with some of the parts removed to more fully illustrate the parts coming under the same. Fig. 8 is an end view of the stop-motion device looking in the direction of arrow *e*, Fig. 5. Fig. 9 is a bottom view of a rotatable disk used on said device and some of the operating mechanism connected therewith. Fig. 10 represents a portion of a notched spring-spindle and its latch, constituting a part of the brake-lever mechanism with which my improved stop-motion mechanism connects, as hereinafter described, part of the knitting mechanism also being shown in said figure. Fig. 11 represents, upon an enlarged scale, part of said spring-spindle, showing the notch formed therein. Fig. 12 represents the central pivoted portion of the brake-lever and the eccentric for operating the brake through its usual connections, and Fig. 13 is an enlarged front view of some of the brake-operating mechanism looking in the direction of arrow *f* in Fig. 4.

Our invention relates more particularly to

machines for knitting underwear; and the object thereof is to provide means for automatically stopping the rotary cam-ring or the needle-cylinder of a knitting-machine (according to which is made to rotate) when any defect occurs in the goods being knitted, from broken needles, or from any cause that will result in holes or depressions being formed therein.

Said invention consists of stop-motion mechanism arranged under the head within the space inclosed by the goods being knitted, having a horizontal ring for supporting said goods and a stop-motion device adapted to bear upon the inner surface of the goods, preferably on a level with the needles, and having a finger which springs forward and catches in any opening or obstruction in the goods being knitted, or any opening or depression caused by broken needles, said finger catching against the fabric causing the shipper and brake-lever of the machine to be operated to stop the knitting portion of said machine, as will be hereinafter more fully set forth.

To enable others skilled in the art to which our invention appertains to better understand the nature and purpose thereof, we will now proceed to describe it more in detail with reference to the accompanying drawings.

In said drawings, *A* represents portions of the frame of the machine. *B* is the stationary head attached thereto; *C*, the stationary needle-cylinder; *C'*, the rotary cam-ring connected with the central vertical shaft *D*, which in practice extends up to connect with and drive the spool mechanism. (Not shown.)

E is the horizontal drive-shaft upon which are mounted the loose and tight pulleys *FG*, respectively, having connected therewith the belt *H* and shipper *I*. Upon said shaft *E* are also mounted the tight pulley *K* and bevel-gear *J*, said pulley *K* being in practice connected by a belt *K'* with the take-up mechanism for keeping the fabric taut as it is being knitted, and the bevel-gear with the mechanism for imparting rotary motion to the cam-ring. Said feed and cam-ring operating mechanism constitute no part of our invention,

and it is therefore deemed unnecessary to illustrate or describe the same to make clear the nature and purpose of our improvements. Said improvements, as before stated, relate 5 solely to the mechanism for operating the usual shipper and brake for applying and disconnecting the driving power to or from shaft D and the needle-cylinder or cam-ring, according to which is made stationary or 10 rotatable on the machine, the needle-cylinder being operated when the fabric revolves with the needles and the cam-ring when said needle-cylinder and the needles are held stationary from rotary motion. In this instance, as will 15 be understood, the drawings represent a machine in which the cam-ring is rotated and in which the needle-cylinder and fabric do not revolve; but since our invention is equally applicable to a machine in which the cam-ring 20 is stationary and in which the needle-cylinder and fabric rotate we do not limit ourselves thereto. In either case our improvements are practically the same in construction and effect the same result in practice—viz., of 25 automatically operating the shipper and applying the brake whenever a defect in the fabric or needles occurs, as previously stated. The description will be confined to the construction shown of a machine having a rotary 30 cam-ring and a stationary needle-cylinder and in which the fabric does not revolve, the same having only a downward feed motion.

The brake L is located under pulley K and is adapted to engage therewith. It is connected with a hub M, pivoted at N to frame A, and to which hub is eccentrically pivoted the hub O of horizontal transverse lever O' near the center of said lever. Lever O' is provided with handles O² O³, one at each end, 40 whereby it may be operated by hand, and is also connected with mechanism for operating it automatically. The handle end O³ of said lever is provided with a lateral hook or projection O⁴, (see Fig. 13,) which catches over the end of a spring-spindle O⁵, arranged in a 45 stationary bearing O⁶. Within said bearing is also arranged another spring-spindle O⁷. Said two spring-spindles are each provided with a cam-hub O⁸ O⁹, which engage and are 50 so constructed that when the spring-spindle O⁷ is turned in one direction the spring-spindle O⁵ will be moved longitudinally in the direction from lever O', and vice versa when turned in the opposite direction. Said cam-hubs O⁸ O⁹ are of ordinary construction, well 55 known to the art, and as we make no special claim thereto it will be unnecessary to show or describe the same in detail.

A constant downward force is imparted to 60 the end O³ of lever O' by a spring O⁹, and said spring-power in practice forces the brake L through the various connecting parts against the periphery of pulley J when said end O³ is released from the end of spring-spindle O⁵. 65 The lever is forced up into engagement with

said spring-spindle by hand to bring the projection O⁴ over the end of the spindle, as is shown in Fig. 13, and when thus held the brake is out of engagement with the pulley K, as is shown by dotted lines in Fig. 4, and is released automatically therefrom to bring said brake in engagement with said pulley. Said automatic release of the lever is ordinarily performed as follows: A vertical spring-spindle P is fitted to slide longitudinally in a vertical guide-opening in the stationary head B, and said spindle is provided near the top with a side cam-notch P', (see Figs. 10 and 11,) with which is adapted to engage a latch P², pivoted to the top of bed B, for holding said spindle in its elevated position until released, said release being usually performed by a notch on the cam-ring or needle-cylinder (according to which is arranged to turn on the machine) coming in contact with and forcing said latch out of engagement with the notch in the spindle, so as to permit its spring P³ to force down the spindle longitudinally. This happens when a defect in the fabric occurs or when one or more of the needles break. Such an occurrence causes the spindle P to be released, and being forced down by its spring its foot P⁴ strikes a finger O¹⁰ (see Fig. 4) and by forcing it down turns spindle O⁷ a partial revolution, thereby forcing the spindle O⁵ back, so as to disengage its end from the brake-lever through the connections previously described. Upon its release said brake-lever is drawn down by its spring, and consequently forces the brake into contact with pulley K, which quickly stops the rotary motion of the parts after the power is removed by the operation of the usual shipper.

The operation of releasing the vertical spring-spindle P not only causes the brake to 105 be applied to pulley K, but also causes the shipper I to be operated to unship the power from the machine by the lower end of said spindle striking the end Q' of horizontal lever Q and forcing its opposite end Q² out of engagement with a notch in the horizontal spindle Q³, so as to permit a spring Q⁴, arranged over the same and engaging with the shipper, to force said shipper to one side, and thereby ship the driving-belt from the tight 110 pulley onto the loose pulley of the machine, in practice the parts being so adjusted that the power is first unshipped and then immediately following the brake applied to stop the rotation of the parts, as in other machines 115 where mechanical power is employed.

Up to the present point in the description the construction is old, except in combination with our improvements, which are as follows: The only change we make in said old parts is to secure a horizontal projection or pin R to the stationary vertical rotatable spring-spindle P, in this instance it being connected with the collar or foot P⁴, secured to the lower end thereof. An angle-plate S, pivoted at S' (see 120

Figs. 1, 2, and 3) to the under side of head B and held stationary thereby, is adapted to engage at one end S² with said pin R and at its opposite end S³ with the curved end T' of a slide-bar T, when the latter is swung around in the operation of the machine, as herein-after described. Said bar T is fitted to slide longitudinally in a frame U, (see Figs. 5 to 8, inclusive,) secured to vertical shaft D and which supports, in addition to said bar, the other operating parts for automatically setting the shipper and brake mechanism in operation, as subsequently described in detail. A constant outward pressure is imparted to force said slide-bar T outward when released, as hereinafter described, by means of a suitable spring T². Frame U being secured to shaft D, as above stated, is carried around with said shaft inside of the fabric V being knitted, and a horizontal disk W, fitted to turn on a suitable bearing U' on said frame U, is arranged to travel around in contact with said fabric during the knitting operation. It continues to thus travel around with its periphery in contact with the inner surface of the fabric indefinitely until some defect in the fabric or needles occurs, when the device is instantly and automatically set in motion to operate the shipper and brake to stop the machine. This is accomplished through suitable connections between slide-bar T and a hook g', mounted on the aforesaid disk W, which is adapted to be sprung out radially from said disk when any hole, depression, or other defective obstruction occurs in the fabric or needles, which will permit said hook to be sprung forward and catch therein.

A horizontal slotted swivel-link h, arranged above the slide-bar T, is pivoted at h' to a fixed bearing. The slot in said link extends nearly its whole length, and in said slot a fixed stud i on the slide-bar fits, (see Fig. 7,) which serves to swing said link on its pivot when the bar is moved longitudinally. It is moved outward automatically by its spring T², as previously stated, and inward by pressing upon its outer curved end T' by hand.

The outer free end of slotted link h is provided with an upward-extending stud h², which is adapted to engage with a notch j' in the outer end of a horizontal lever j, pivoted at j² to a fixed bearing. The inner free end of said lever j engages with the inner free end of another horizontal lever, k, pivoted at k' to a fixed bearing. Said inner end of lever k is provided with a shoulder k² and with a cam edge k³, with which the notched hub l' of lever l is adapted to engage, the shoulder l² of said hub l' being adapted to bear against the shoulder k² of lever k when the parts are locked with the slide-bar T forced in toward shaft D, as is shown by full lines in Fig. 5.

Lever l and its hub are held locked when the slide-bar is thus forced inward, by said lever lying between a fixed pin m in disk W

and the end g² of an arm g³, extending inward from a slide g, to the outer end of which is secured the hook g', previously referred to. Said slide is fitted to move radially in a suitable guide-slot g⁴ in disk W and is provided with a suitable spring g⁵ for exerting a constant outward pressure thereon, so that the hook g' will be sprung out instantly and automatically when any opening or depression comes in line therewith in the fabric, as previously stated, during the knitting operation.

The slotted link h and levers j, k, and l are each provided with suitable springs for forcing them into their normal positions when the lateral pressure thereon is released.

By the foregoing construction and arrangement of the parts mounted on the rotating frame U it is obvious that so long as the knitting process goes on properly and there is no break in the fabric or needles or other defect that will permit the slide g and its hook g' to spring forward said locking device mounted on frame U will continue to be rotated by shaft D, with the periphery of disk W and its hook in contact with the inner surface of the fabric, said disk being held from turning, so as to always keep said hook in proper position to catch in any hole or depression in the fabric or in the line of needles. To facilitate the hook g' slipping freely along the surface and prevent its catching when no obstruction occurs therein, the end is curved, as is shown in Figs. 5 and 9, so that it will slip along smoothly over said surface. The disk W is held locked when the machine is running properly by the arm g³ bearing against the lever l and holding said lever between said arm and the fixed pin m, in which position a shoulder on hub l' engages shoulder k² on lever k, as previously described. After the machine has been automatically stopped, as hereinafter described, and the break repaired the automatic stop mechanism mounted on frame U is reset again in its normal position, ready to operate at the next break by simply pushing inward by hand on the curved end of slide-bar T, said operation causing all the operating parts to be moved back into their locked positions, as is shown in Figs. 5, 6, 8, and 9. Fig. 7, in which the disk W is left off, shows the parts under said disk in the positions that they occupy after they are released and sprung forward.

The spring g⁵ for operating the slide g is in practice made just sufficient in strength to properly force said slide forward, but not to unduly bear upon the surface of the fabric.

An oil-pan X is preferably arranged under the bearing of frame U to catch any surplus oil used in oiling that part of the machine and prevent its falling upon the fabric underneath. A circular wire frame Y is also arranged under said frame U below said oil-pan for holding the fabric expanded in proper position, as is shown in Figs. 2 and 3. Said wire frame is mounted on a loose sleeve Y', fitted to slide

freely on a vertical spindle Y^2 , extending down in alinement with and from the center of shaft D , and provided with a suitable collar Y^3 at the bottom to prevent the frame from slipping off of said spindle when the fabric is removed.

During the knitting operation the pressure of the fabric holds said wire frame from slipping down, owing to the inward inclination 10 of the lines of the fabric, as is also shown in Figs. 2 and 3.

It is obvious that the details of construction of our improved automatic stop mechanism may require varying in practice to meet different circumstances, and we therefore reserve 15 the right to make such modifications therein as may be advisable coming within the scope of our invention.

Our stop mechanism may be applied either 20 to a knitting-machine having a stationary cam-ring and a rotary needle-cylinder wherein the fabric revolves with the needle-cylinder or to a knitting-machine having a rotary cam-ring and a stationary needle-cylinder, the fabric in 25 that case having no rotary motion.

As previously stated, we are aware that it is not broadly new to apply a stop-motion mechanism to a knitting-machine for the purpose described, the same having been done in various 30 ways to be operated by hand and automatically by a break in the thread or yarn between the spools and fabric being knitted; but we are not aware that said mechanism has heretofore been operated by a device arranged 35 within the space inclosed by the fabric being knitted and set in operation automatically by contact therewith when any defect occurs therein—as, for instance, when the needles break and permit the fabric to be forced outward 40 by the finger g' into the depression thus formed or when any opening in the fabric occurs from defective knitting into which said finger may enter and catch, and thus cause the operation of the stop mechanism to unship the 45 power and stop the machine, as hereinafter described. This feature we believe to be wholly new in a machine of this class. By thus controlling the operation of the machine by the condition of the needles and fabric while 50 knitting, whereby said machine is stopped instantly the moment any defect in said fabric comes in line with the hook or projection g' of the stop-motion device previously described, a large saving is effected in the knitting operation, both in time and in the fabric being 55 knitted and also in labor. Since but little attention is required from the attendant or operative in running a machine equipped with our improvement, we effect a large saving in 60 the fabric and labor, and consequently in the total net cost of production.

Having now described said invention, what we claim as new, and desire to secure by Letters Patent, is—

65 1. In a knitting-machine, the supporting-

frame, the shipper and brake, means for connecting said shipper and brake with spring-spindle P , means for detachably supporting said spring-spindle, and said spring-spindle, having a lateral projection, in combination 70 with angle-plate S , pivoted to a stationary bearing, and adapted to engage at one end with said lateral projection on the spring-spindle, and at its opposite end with the outer end of a slide-bar T , fitted to slide longitudinally in frame U ; said frame U , secured to vertical rotary shaft D ; said shaft D ; slide-bar T , provided with the stud i ; its spring T^2 ; slotted spring-link h , arranged above pivoted slide-bar T , and provided with the 80 stud h^2 ; spring-lever j , pivoted at j^2 , and provided with the notch j^3 ; spring-lever k , pivoted at k' and provided with the shoulder k^2 , and cam edge k^3 ; spring-lever l , to disk W , and provided with a shoulder or projection l^2 on its hub adapted to engage with shoulder k^2 ; holding-pin m , against which lever l is adapted to bear; slide g , fitted in a slot in disk W ; arm g^3 extending back therefrom and engaging with lever l ; spring g^5 , 90 for forcing slide g outward; hook g' , formed upon, or secured to the outer end of slide g , and the aforesaid disk W , adapted in connection with its hook g' to bear upon the inner surface of the fabric being knitted, substantially as and for the purpose set forth. 95

2. In a knitting-machine, the combination with the usual spring-spindle P having a lateral projection, of the pivoted angle-plate S adapted to engage at one end therewith, and 100 at its outer end with the outer end of a slide-bar T ; said slide-bar, fitted in a frame U secured to shaft D ; means for forcing said slide-bar outward; disk W , pivoted to frame U ; its slide g , fitted in a slot formed therein 105 and provided with means for forcing it outward, and means operatively connecting the slide-bar T with said slide g , for locking the various parts when the slide-bar is forced in by hand, and which may be unlocked automatically by turning the disk W , substantially as and for the purpose set forth. 110

3. In a knitting-machine, a stop-motion device arranged within the space inclosed by the fabric being knitted, connected with shaft 115 D so as to turn therewith, and whose outer end bears against the inner surface of said fabric in the operation of knitting, said device comprising the frame U , secured to shaft D ; slide-bar T , fitted therein and having means for forcing it outward, and also adapted to engage with a pivoted lever in turn arranged to engage with the usual spring-spindle P ; disk W , mounted and fitted to turn on the outer end of frame U ; its slide g , provided with hook g' ; means for forcing said slide outward, and means for connecting said slide g with slide-bar T , consisting of pivoted, 120 spring-link h ; its connection with slide-bar T ; pivoted spring-levers j , k and l , and means 125 for connecting slide g with slide-bar T ; pivoted spring-levers j , k and l , and means 130

for holding said lever L, while the device is traveling around inside of the fabric in contact therewith, during the proper knitting thereof, substantially as and for the purpose set forth.

4. In a knitting-machine, the combination of the usual spring-spindle P, having a lateral projection, the fabric V and shaft D, with the circular wire frame Y arranged to slide on a central, vertical spindle Y², extending down from shaft D, and adapted to bear upon the inner surface of the fabric, to hold it expanded; frame U secured to said shaft D; slide-bar T fitted therein, and having means for forcing it outward, and also adapted to engage with a pivoted lever S, in turn arranged to engage with the usual spring-spindle P; said lever S, disk W, mounted and fitted to turn in the outer end of frame U; its slide g provided with hook g', means for forcing said slide outward, and means for connecting said slide g with slide-bar T, consisting of pivoted, spring-link h, its connection with slide-bar T, pivoted spring-levers j, k and l, and means for holding said lever l while the device is traveling around inside of the fabric in contact therewith, during the

proper knitting thereof, substantially as and for the purpose set forth.

5. In a knitting-machine, the combination 30 of slide-bar T, fitted in frame U, and having means for forcing it outward; pivoted spring-link h, engaging with said slide-bar and with pivoted spring-lever j; said spring-lever j, engaging with pivoted spring-lever k; said 35 spring-lever k, engaging with pivoted spring-lever l; said lever l; means for holding it nominally locked from lateral motion; slide g, fitted in disk W, provided with hook or projection g', and with means for forcing it 40 outward; and said disk W, substantially as and for the purpose set forth.

6. In a knitting-machine, a shaft D, having thereon a circular frame arranged inside of the completed fabric, a vertical spindle extending downward from said shaft D, a sleeve fitted to slide upon said spindle and carrying said circular frame, and a stop-collar on the lower end thereof, substantially as described.
